UNITED STATES PATENT OFFICE.

HENRY HERPERS, OF NEWARK, NEW JERSEY.

INKING-PAD FOR HAND-STAMPS.

SPECIFICATION forming part of Letters Patent No. 390,858, dated October 9, 1888.

Application filed December 24, 1887. Serial No. 258,870. (No model.)

To all whom it may concern:

Be it known that I, HENRY HERPERS, of Newark, in the county of Essex and State of New Jersey, have invented certain new and useful Improvements in Inking-Pads for Hand-Stamps, of which the following is a specification.

This invention relates to improvements in inking-pads used for inking the type faces of hand-stamps; and the object of my invention is to provide a new and improved pad of this kind which can absorb and retain a large supply of ink and in which the ink on the surface does not become so moist or fluid as to clog the type and produce blurred impressions.

My invention consists in a marking-pad composed of a sheet of cork partially or entirely saturated with printing or marking ink.

In the accompanying drawing a combined cross-sectional and perspective view of my improved inking-pad for hand-stamps is shown.

The inking-pad A is composed of a sheet of cork of greater or less thickness, which cork sheet is thoroughly or partially saturated with printing-ink, such as is usually used on pads for hand stamps. The cork has the property of absorbing the ink and retaining it in such a manner that the surface of the pad appears to be perfectly dry; but when the type face of a hand-stamp is brought in contact with the face or top of the pad sufficient ink adheres to said type-face to produce a clear and distinct impression. The ink never floats on the face of the cork pad, as it does on the felt, cotton, or other pads, especially during warm weather, or when the air is very humid.

As my improved cork inking-pad at all times remains comparatively dry on the surface, too much ink is never applied to the type faces, which do not become clogged, and thus the impressions produced are not blurred and the ink applied on the sheet by the stamp cannot be smeared or wiped over the sheet, as might happen if too much ink had been transferred from the pad to the type face or the ink been too liquid. The surface of the cork is yielding and elastic, and does not injure the rubber type; but it is by no means as yielding as a felt or cotton pad. The type cannot be pressed into the cork face deeply, as into a felt or cotton cushion, and thus no ink is applied on the sides of the type, as is apt to occur when using cotton or felt pads.

To protect the sheet of cork from being broken, the same is placed in a wooden or metal casing, B, which can be provided with a cover to protect the surface of the pad from dirt and dust.

Having thus described my invention, I claim as new and desire to secure by Letters Patent—

An inking-pad for hand-stamps composed of a sheet of cork partially or entirely saturated with printing-ink, substantially as shown and described.

In testimony that I claim the foregoing as my invention I have signed my name in presence of two subscribing witnesses.

HENRY HERPERS.
